UNITED STATES PATENT OFFICE.

ROBERT CRAWFORD JOHNSON AND MATTHEW HENRY MYERS, OF LEICESTER, ENGLAND.

CURTAIN-ROD.

No. 872,565.

Specification of Letters Patent.

Patented Dec. 3, 1907.

Application filed May 24, 1907. Serial No. 375,510.

To all whom it may concern:

Be it known that we, ROBERT CRAWFORD JOHNSON and MATTHEW HENRY MYERS, subjects of the King of Great Britain, residing at 5 2 London road, Leicester, Leicestershire, England, have invented new and useful Improvements in Curtain-Rods, of which the following is a specification.

Our invention relates to rods especially designed for supporting casement curtains but also applicable for carrying curtains of other kinds, the object of our invention being to provide a rod which can be fixed without the necessity for using supporting brackets and 15 upon which the curtains can be easily drawn without the usual cords and pulleys.

The rod constructed according to our invention is of double channel shape in transverse section and somewhat similar to the 20 letter H except that the bar or plate on one side of the connecting web is advantageously of less height than upon the other side.

The broad side of the bar is adapted to be directly connected to the window frame by 25 screws or other fastenings and the narrow side is designed to carry runners from which the curtains are suspended. These runners are preferably in the form of stirrups carrying rollers for running upon the bar in order 30 to afford freedom of travel for the carriers, suitable eyes being provided for carrying the curtains in the ordinary manner.

To enable our invention to be fully understood we will describe it by reference to the 35 accompanying drawing, in which:—

Figure 1 is a front elevation of our improved curtain rod with a runner upon it. Fig. 2 is a plan view of the same. Fig. 3 is a section on the line 3—3, Fig. 1, and Fig. 4 is a 40 view similar to Fig. 3 illustrating a modification.

a is the double-channeled bar, the back of which is made broader than the front and is adapted to be secured to the window or other 45 frame by screws b, b or other fastenings, and c indicates one of the several runners adapted to travel on the bar and carry the curtains. As shown in Figs. 1, 2 and 3 the runner is in the form of a stirrup d carrying rollers e, e 50 which run in the channels of the bar.

When the rod is fixed in situations in which the carrier would be liable to be pulled off we advantageously fix angle pieces f, f or other suitable stops at the ends thereof. Instead of the rollers e, e running in the channels of the bar, the carrier c may be constructed so that the said rollers will run upon the edges of the narrow portion of the bar, as shown in Fig. 4, the ends of the stirrup being extended into the channels to retain the carrier upon the bar. 55

The eyes to which the curtain hooks are connected may be arranged in any suitable position. In practice, however, we prefer to provide the carrier with two eyes g, g in vertical alinement, the said eyes being adapted to receive a special hook h of the kind shown in Figs. 3 and 4, the tongue of which hook passes through both eyes. This arrangement of hooks and eyes serves to distribute 65 the pull upon the carriers so that the latter run more smoothly than would be the case if the whole weight was carried by a single eye. 70

It will be obvious that instead of attaching 75 the bar or rod directly to the framing of a window or the like, it may be carried by adjustable or other brackets adapted to receive it.

Having now particularly described and ascertained the nature of our said invention and in what manner the same is to be performed, we declare that what we claim is:— 80

The combination with a curtain rod or bar of double channel section having the plate on 85 one side of the channel broader than the plate on the other side of the said channel, of runners adapted to travel on the said rod or bar and to have curtain hooks attached to them, each runner being provided with two 90 eyes placed one above the other to receive the straight shank of a hook, substantially as described.

ROBERT CRAWFORD JOHNSON.
MATTHEW HENRY MYERS.
